UNITED STATES PATENT OFFICE.

NELSON J. RUSSELL, OF CHICAGO, ILLINOIS.

FUEL-SAVING DEVICE FOR FURNACES.

1,392,453.

Specification of Letters Patent.

Patented Oct. 4, 1921.

Application filed December 27, 1920. Serial No. 433,345.

To all whom it may concern:

Be it known that I, NELSON J. RUSSELL, a citizen of the United States, and a resident of Chicago, in the county of Cook and 5 State of Illinois, have invented certain new and useful Improvements in a Fuel-Saving Device for Furnaces, of which the following is a specification.

This invention relates generally to furnaces, but has particular relation to a fuel saving device adapted for use in various types of furnaces, stoves, and the like, which device may be appropriately called "a fire-chamber chimney," on account of the character of its construction and of its location 10 when in use.

The invention consists in certain peculiarities of the construction, novel arrangement and combination of its parts as will be hereinafter more fully set forth and specifically claimed.

The principal object is to provide a very simple and economically constructed, yet strong, durable, highly efficient and movable 25 device to be used in the fire-pots or chambers of furnaces, stoves and the like, for supplying preheated air and an augmented quantity of oxygen to the burning fuel and at proper points, in order to effect, as nearly 30 as possible, complete combustion of the fuel and thereby economize in the quantity thereof used.

A further object is to provide a movable and removable device of the above mentioned general character, which can be used 35 in the fire-chambers of furnaces and the like without any changes, whatsoever, in the construction thereof, and without being permanently attached to any part of the furnace or stove, yet can be so located, or readily shifted or adjusted in its position within the fire-chamber to furnish air and oxygen at the right point or points to insure the best results in the combustion of fuel.

40 Other objects and advantages of the invention will be disclosed in the following description and explanation.

In the accompanying drawing which serves to illustrate an embodiment of the 45 invention—

Figure 1 is a fragmentary view of a portion of a furnace showing it equipped with a pair of my newly invented fuel saving devices.

50 Fig. 2 is a vertical central sectional view

of the device showing it on an enlarged scale from that shown in Fig. 1.

Like numerals of reference refer to corresponding parts throughout the views of the drawing.

The reference numeral 5 designates a portion of a furnace of the ordinary or well known construction in the fire-pot or chamber 6 of which is located on the upper surface of the grate, which latter is designated 60 as a whole by the numeral 6^a, a pair of fuel saving devices constructed according to my invention. As shown in said view of the drawing, the devices are located near the front wall of the furnace and directly on 65 the grate bars but are spaced apart and each has its globular expansion chamber 7 located in such a way with respect to the bed of coals 8 as to be mainly extended above the upper surface of said bed. The 70 device is by preference made of a single 75 piece or casting, and comprises a hollow base portion 9 provided at its lower edge with an out-turned flange 10 to rest on the 80 grate bars of the furnace and to assist in 85 supporting the device. Extending from the upper central portion of the base 9 and communicating therewith is a chimney 11 which is by preference slightly tapered toward its upper end. On the upper portion 90 of the chimney 11 and surrounding the same is the globular expansion chamber 7 of the device, which chamber or casing is provided with a horizontally disposed and circumferentially extended opening or slot 12 which 95 is broken by means of a plurality of connecting ribs 13 which unite the lower edge of the upper part 14 of the extension chamber or casing with the upper edge of the lower part 15 as will be readily understood 100 by reference to Fig. 2 of the drawing. The casing or chamber 7 is reinforced at the lower edge of the part 14 by means of a bead or enlargement 16 which has its upper surface downwardly inclined as shown 105 to prevent lodgment of fuel thereon when the same is being fed to the fire-pot or chamber through the door-way or door-ways of the furnace.

The upper edge of the part 15 of the expansion chamber 7 is also by preference reinforced by means of a bead 17 which extends around the upper edge of the part 15 and is employed to give additional strength to the said part and also to co- 110

operate with the flat surface of the lower edge of the part 14 of the casing 7 to provide a passageway having its adjacent surfaces flat and in parallelism with one another, for directing the heated air from the expansion chamber as it is discharged therefrom. The base 9, chimney 11, and casing 7 is by preference provided with strengthening ribs 18 at least one of which ribs is 5 provided at the juncture of the expansion chamber 7 with the chimney 11 with an enlargement 19 having therein a lateral opening 20 for the purpose to be presently explained.

10 15 As shown, the upper end of the chimney 11 is extended above the slot or discharging opening 12 but terminates some distance below the arched dome of the expansion chamber or casing.

20 The operation of the device is simple and as follows:

25 One or more of the devices may be placed in the fire chamber of the furnace or stove and at any desired location on the grate thereof, but by preference near the front wall of the furnace or the wall adjacent the door-way leading to the fire chamber of the furnace or stove. When in this position the base and chimney of the device will be 30 covered or surrounded by coal, but it will be understood that the expansion chamber or casing 7 will be located above the upper surface of the bed of fuel in such a way as not to prevent or materially retard the 35 discharge of air through the discharging opening or slot 12 of said chamber.

40 After the fire has been started, the air drafts through the ash pit and flue of the furnace or stove acting in their usual or normal ways, or which may be regulated by means of dampers in the well known way, will ascend from the ash pit into the base 9 of the device where the air will be heated to a degree and from the hollow base 9 it

will pass through the chimney 11 where it 45 will be further heated and from thence will pass into the expansion chamber or casing 7 where it will be heated to a high degree of temperature, and be caused to pass from said chamber through the opening 12 therein 50 in a flat circular stream over the bed of coals to commingle with the particles of combustion within the fire chamber thus causing the latter to be more perfectly consumed.

55 By the use of my device, it is manifest that it can be placed in any suitable location on the grate by simply cleaning away a place sufficiently large to permit the bottom of the base to rest on the grate bars when the fuel may be placed around the device or 60 shoveled in through the doorway of the furnace in the usual manner. If it is desired to move the device from one point to another on the grate it is obvious that a poker or rod can be inserted in one of 65 the openings 20, which will enable the device to be moved to any suitable point or removed from the furnace while hot, if desired.

70 It is further obvious that as the device is adapted to be movably mounted on the grate that the grate bars can be rocked for cleaning the same, or they may be otherwise cleaned without interference with the device.

75 Having thus fully described my invention, what I claim as new, and desire to secure by Letters Patent is—

A fuel saving device, consisting of a relatively flat hollow base having its lower portion open, an upright chimney centrally mounted on the upper surface of the base 80 in communication with the cavity thereof and a casing surrounding the upper portion of the chimney and mounted thereon, said casing forming an expansion chamber and provided with a horizontally disposed 85 opening for the discharge of air.

NELSON J. RUSSELL.
